UNITED STATES PATENT OFFICE.

JOHN P. SYKES, OF WALLINGFORD, AND HARMON E. STOVER, OF PHILADELPHIA,
PENNSYLVANIA.

JIG FOR ASSEMBLING LOCOMOTIVE FRAMES.

Application filed July 26, 1922. Serial No. 577,617.

To all whom it may concern:

Be it known that we, JOHN P. SYKES and HARMON E. STOVER, citizens of the United States, residing, respectively, in Wallingford, Delaware County, Pennsylvania, and Philadelphia, Pennsylvania, have invented certain Improvements in Jigs for Assembling Locomotive Frames, of which the following is a specification.

10 Our invention relates to certain improvements in jigs for assembling the side frames of a locomotive so as to insure the proper alignment of one frame in respect to another and the correct assembling of the several 15 parts of a locomotive, which are secured to the side frames.

This invention is an improvement on the construction for which a patent was granted to John P. Sykes, February 26, 1921, No. 20 1,369,574.

The object of the present invention is to construct the jig so that, when the locomotive frames and the parts assembled thereon are to be removed, the frames can be removed 25 bodily with the pedestal caps in position. This is accomplished by making the saddle structures collapsible.

In the accompanying drawings:

Fig. 1 is a plan view of our improved jig 30 for supporting and aligning locomotive and like frames, illustrating a locomotive frame in position;

Fig. 2 is a side view;

Fig. 3 is a plan view of one of the saddles;

Fig. 4 is a side view of the saddle shown in Fig. 3;

Fig. 5 is an end view of the saddle;

Fig. 6 is a sectional view on the line 6—6,

40 Fig. 3;

Figs. 7 and 8 are detached perspective views of the spacing plates, which are located between the two sections of each saddle;

Fig. 9 is a detached perspective view of 45 a spacing plate for the abutment blocks;

Fig. 10 is a detached perspective view of the two abutment blocks; and

Fig. 11 is a detached perspective view of 50 the two fixed blocks, which are secured to one of the sections of a saddle.

Referring to the drawings, 1 is a foundation plate of any length desired. Mounted on this plate, in the present instance, are two saddles. Each saddle structure 2 consists of 55 two sections 3 and 4 mounted on a base plate

5. The foundation plate has two longitudinal slots 1^a therein, which are undercut to receive the heads of bolts 6 and washer plates 7. The bolts extend through openings in the base plate 5 and hold the base 60 plate firmly to the foundation plate after adjustment.

The two sections 3 and 4 of the saddles are mounted movably on the base plate and are secured firmly thereto by clamp plates 8 65 and bolts 9, as shown in Fig. 5. When the bolts 9 are backed off, the sections are released so that they can be moved towards or from each other to accommodate the frames of locomotives of different gages or types. 70

Between the two sections 3 and 4 of the saddle are spacing plates made as shown in Figs. 7 and 8. The upper spacing plate 10 is bent at right angles to form a top section 11 and a side section 12. The top section is 75 wider than the side section, as shown in Fig. 7. This section is adapted to grooves in the saddle sections 3 and 4. The lower spacing plate 14, Fig. 8, is bent at right angles to form a bottom section 15 and a side section 16. 80

These spacing plates may be of different widths, depending upon the gage of the locomotive. When the plates are in position, as shown in the drawings, a series of bolts 17, 85 located at each side of the saddle, connect one section to the other, clamping the sections to the spacing plates, as shown—making a substantial and rigid construction.

On the section 3 of the saddle is a fixed 90 bracket 18, which extends through the axle box openings between the pedestals of one of the side frames of a locomotive. In this bracket is a series of openings 19 for the screws, which clamp the frame to the bracket. The frame *w* rests on the bracket, as shown in Fig. 4. On the section 4 of the saddle is a bracket 20. This bracket is grooved at the top and at one side to receive the top and side fixed blocks 21 and 22, 100 which are firmly secured in position by bolts 23. The bracket 20 has two slots 24 at the top, in the present instance, and two slots 25 at the side.

26 is the top abutment block and 27 is the side abutment block. The abutment blocks are spaced from the fixed blocks by a right angled spacing plate 28, Fig. 9. The plate has rounded corners to allow for the fillets in the locomotive frames and extends over 105 110

2
the top of the bracket 20 and on each side thereof, as shown by dotted lines in Fig. 5. When this spacing plate is in position, the abutment blocks are held firmly against the 5 plate by bolts 29, which extend through the slots in the bracket and through the blocks.

When the abutment blocks are in proper 10 position, the frame x' is mounted on the bracket 20 of the section 4 of the saddle and clamped against the abutment blocks.

The frame x' is then moved to the proper position in respect to the frame x and is also clamped in position—one frame being in proper alignment with the other frame.

15. The parts of a locomotive can then be assembled on the frames.

When it is desired to remove the locomotive frames with the attached parts from the saddle the bolts 17 can be loosened to allow 20 for the removal of the spacing plates 10 and 14.

14. The clamp bolts are backed off and either one of the sections of the saddle can be moved on the base plate until the frames are free thereof. In the meantime, the locomotive 25 has been engaged by the hoisting mechanism of a crane. The crane is then operated to lift the locomotive parts free of the jig. This can be accomplished without removing the pedestal caps from the frames.

30. While the invention is particularly adapted for use in supporting locomotive frames, it will be understood that the jig can be used for supporting frames of other machines without departing from the spirit 35 of the invention.

We claim:

1. The combination in a jig, of a foundation 40 plate; a saddle structure consisting of a base plate and two sections secured thereto, each section having a bracket to support a frame of a locomotive; spacing plates between the sections of the saddle; and bolts connecting the sections.

2. The combination in a jig, of a foundation 45 plate; a saddle structure adjustably mounted thereon, said saddle structure consisting of a base plate and two sections, said sections being adjustably mounted on the base plate and having brackets to support the frames of a locomotive; upper and lower spacing plates located between the

sections of the saddle; and bolts connecting the sections.

3. The combination in a jig, of a foundation plate; a saddle structure adjustably 55 mounted thereon, said saddle structure consisting of a base plate and two sections adjustably mounted on the base plate; two angular spacing plates located between the two sections; and bolts securing the two sections together and to the spacing plates.

4. The combination in a jig, of a foundation plate; a saddle structure mounted on the foundation plate, said saddle structure consisting of a base and two sections, each 65 section having a bracket to support a frame of a locomotive, one of said brackets having a spacing plate; and an abutment block adjustably mounted on the bracket.

5. The combination in a jig, of a foundation plate; a saddle structure mounted thereon, said saddle structure consisting of a base and two sections, said sections being adjustably mounted on the base, each section having a bracket to support a frame of a locomotive; and two abutment blocks adjustably mounted on one of said brackets, one block being secured to the top of the bracket and the other block being secured to one 75 side thereof.

6. The combination in a jig for supporting the frames of a locomotive, of a saddle having two sections spaced apart, each section having a bracket, one of said brackets having slots at the top and at one side; abutment blocks mounted on the bracket; and bolts extending through the slots of the bracket and engaging the abutment blocks.

7. The combination in a jig for supporting the frames of a locomotive, of a saddle having two sections spaced apart, each section having a bracket, one of said brackets having slots at the top and at one side; abutment blocks mounted on the bracket; bolts extending through the slots of the bracket 90 and engaging the abutment blocks; two fixed blocks secured to the bracket; and a spacing plate between the abutment blocks and the fixed blocks.

JOHN P. SYKES.
HARMON E. STOVER.
